DEVICE FOR INDICATING RESULTS OF
BOWLING GAMESJames L. Hunold, Mendham, N. J., assignor to
Julius Braun, Linden, and Archie Kass, New-
ark, N. J.

Application July 21, 1937, Serial No. 154,738

3 Claims. (Cl. 273—44)

This invention relates to bowling games; and gagement with contact 24, thus maintaining open a circuit through an indicator lamp 25. When pin 11 is knocked down, the circuit through relay 22 is broken, allowing engagement of contacts 23 and 24 and closing the circuit through indicator 25.

As is well known, in a bowling game, the frequent resetting of the pins is a source of annoyance. Heretofore, there have been devised devices for automatically resetting the pins in a bowling game. However, such devices merely reset the pins, but in no way indicated which pins had been knocked down by the bowler; and consequently when the automatic resetting device is used, considerable of the features of the bowling game was sacrificed.

It is, therefore, an object of this invention to provide in combination with an automatic pin resetting device, means for automatically indicating the various pins which have been knocked down by a bowler.

It is a further object of this invention to provide a circuit closing device which can be effectively used for automatically indicating results in any kind of game or contrivance.

These and other advantageous objects, which will later appear, are accomplished by the simple and practical construction and arrangement of parts hereinafter described and exhibited in the accompanying drawing, forming part hereof, and in which:

Fig. 1 is a sectional view of a bowling pin with resetting device and wiring for indicating results,

Fig. 2 is a view similar to Fig. 1 of a modification of the invention, and

Fig. 3 is a diagrammatic view of means for indicating results in a bowling game.

Referring to the drawing, in Fig. 1 there is shown a bowling pin 11, resting upon a base 12, having an aperture 13 through which passes a core 14 of an electromagnet 15 attached to the underside of the base 12. The pin 11 has attached to the underside thereof a metal plate 16 having a plug 17 extending up into the pin. Attached to the plug 17 is a metal wire 18 which passes over a metal pulley 19, which is constantly urged to rotate counter-clockwise by spring mechanism of the shade roller type, or other mechanisms heretofore employed in resetting bowling pins. The pulley 19 is provided with a hub 20, which constantly engages a contact brush 21, connected to a relay 22.

As will be seen from the wiring diagram, an electrical circuit is completed through pulley 19, wire 18, plug 17, core 14, to the source of power 28. When the pin 11 is in position on the base 12 as shown in Fig. 1, the circuit is closed and relay 22 energized to attract contact 23 from en-

5 In Fig. 3 is shown an indicator with a plurality of lamps 27 arranged in the same order as the pins 11 are arranged on the base 12, and when the lamps 27 are lighted, a player can readily determine the result of his bowling.

10 In Fig. 2 is shown a modified form of the invention in which a pin 30 has a wire 31 attached thereto. The pin is maintained upright by an electromagnet 33 having a core 32 as described in connection with Fig. 1. The wire 31 passes over a metal pulley 34, having a hub 35 of insulating material provided with a metal segment 36, engaging brushes 37, which close a circuit through an indicator lamp 38.

15 When the pin 30 is knocked down, contact with the core 32 is broken and the winding mechanism in the pulley 34 will draw the pin upward. As the pulley rotates, the segment 36 will intermittently engage the brushes 37 and will cause an intermittent flashing of the lamp 38.

20 From the above description it will be seen that there has been provided relatively simple and effective means for closing an electrical circuit through lamps in order to indicate the results of a bowling game or similar games and contrivances. While this invention has been specifically described in connection with a bowling game provided with an automatic resetting device, it is obvious that it can be well applied to other games without materially departing from the scope of the invention.

25 The foregoing disclosure is to be regarded as descriptive and illustrative only, and not as restrictive or limitative of the invention, of which obviously embodiments may be considered including many modifications without departing from the scope herein indicated and denoted in the appended claims.

30 Having thus described my invention, what I claim as new and desire to secure by Letters Patent is:

35 1. In a bowling game, a base, a bowling pin supported in upright position on said base, said pin having a metal plate attached to the bottom thereof, an electromagnet mounted on the underside of said base and arranged to maintain the pin in an upright position when energized, a core for said electromagnet adapted to make an electrical connection with said plate, a metal 40

pulley mounted above said pin, an electrical conducting wire attached to said plate and passing through the pin and over said pulley, a normally closed switch, a relay adapted to hold said switch open, means for connecting the relay to the pulley, said electromagnet being connected to a source of power, said relay being in circuit with the core of the magnet and connected to a source of power, means for winding said wire on the pulley when the pin is dislodged from the base, and an incandescent lamp, said switch closing a circuit through said lamp when the relay is deenergized by the breaking of the circuit therethrough resulting from the breaking of contact between said plate and core.

2. In a bowling game, a base, a bowling pin supported in upright position on said base, said pin having a metal plate attached thereto, an electromagnet mounted on the underside of said base and arranged to maintain the pin in an upright position when energized, a core for said electromagnet adapted to make an electrical connection with said plate, a pulley mounted above said pin, an electrical conducting wire attached to said plate and passing over said pulley, a normally closed switch, a relay adapted to hold said switch open, said electromagnet being connected to a source of power, said relay being in circuit with the core of the magnet and connected to a source of power, means for winding said wire on the pulley when the pin is dislodged from

the base, and an indicating device, said switch closing the circuit through said indicating device when the relay is deenergized by the breaking of a circuit therethrough resulting from the breaking of contact between said plate and core. 5

3. In a bowling game, a base, a bowling pin supported in upright position on said base, said pin having a metal plate attached to the bottom thereof, an electromagnet mounted on the underside of said base and arranged to maintain the pin in an upright position when energized, a core for said electromagnet adapted to make an electrical connection with said plate, a metal pulley mounted above said pin, an electrical conducting wire attached to said plate and passing over said pulley, a normally closed switch, a relay adapted to hold said switch open, said pulley having a metal hub, a contact brush constantly engaging said hub and connecting the relay to the pulley, said electromagnet being connected to a source of power, said relay being in circuit with the core of the magnet and connected to the source of power, means for winding said wire on the pulley when the pin is dislodged from the base, and an indicating device, said switch closing a circuit through said indicating device when the relay is deenergized by the breaking of the circuit therethrough resulting from the breaking of contact between said plate and core. 10 15 20 25 30
